UNITED STATES PATENT OFFICE.

HARRY K. DICKERMANN, OF BUFFALO, NEW YORK, ASSIGNOR TO F. N. BURT COMPANY, LIMITED, OF TORONTO, ONTARIO, CANADA, A CORPORATION OF ONTARIO, CANADA.

BOX MACHINE.

Application filed May 27, 1922. Serial No. 564,040.

To all whom it may concern:

Be it known that I, HARRY K. DICKERMANN, a citizen of the United States, residing at Buffalo, in the county of Erie and 5 State of New York, have invented certain new and useful Improvements in Box Machines, of which the following is a full, clear, and exact description, such as will enable others skilled in the art to which 10 it appertains to make and use the same.

This invention relates to machines to be utilized in the manufacture of paper boxes and with respect to its more specific features to automatically operated power 15 driven machines of this character.

An object of this invention is to provide an improved machine of this character in which all the operations are performed automatically.

20 Another object is to provide an improved machine of this character in which there is provided an improved form of press to assemble two elements of a box together.

Another object is to provide an improved 25 and automatically acting means to convey the various elements of the box to the press.

Another object is to provide an improved 30 and automatically acting means to hold the various elements of the box to insure proper action thereon by the press.

Another object is to provide an improved 35 and automatically acting means for disengaging and discharging the completed boxes from the press.

Another object is to provide an improved 40 and efficient means for automatically assembling the various elements of the boxes to be joined.

Another object is to provide an improved 45 form of combined glue drying heater and press.

Other objects will be in part obvious and in part pointed out hereinafter.

50 The invention accordingly consists in the features of construction, combinations of elements and arrangement of parts which will be exemplified in the construction hereinafter set forth, and the scope of the application of which will be indicated in the following claims.

As an embodiment of the invention there

is illustrated in the drawing a machine for assembling elements of boxes which are to be glued together. The drawings include— 55

Figure 1, a plan view of the machine;

Fig. 2, a side view of the machine;

Fig. 3, an end view;

Fig. 4, a detailed view of portions of the feed mechanism for the various portions 60 of the boxes and means for pressing these portions together;

Fig. 5, a detailed view of the press and its manner of operating on the parts of the boxes; 65

Fig. 6, showing the means for feeding the portions of the boxes to position at the press;

Fig. 7, a detailed view of means for drying the glued portions; 70

Fig. 8, a detailed view of the means for feeding the box portions to the press and the means for holding the respective portions in proper position at the press;

Fig. 9, showing the means for applying 75 glue to the portions of the boxes;

Fig. 10, a detailed view of the means for holding one portion of the box in position at the press; and

Fig. 11, which shows the character of 80 the completed article.

The machine illustrated in the drawings is adapted to glue elements of a box together. In the present embodiment, these elements include a box portion 14 and a 85 face-piece 15 as shown in Fig. 11. Together they form the cover of a box used for containing material such as face powder or other such material. Usually such boxes are provided with a more or less ornamenteally decorated exterior. Each portion of the box is made fundamentally of comparatively stiff paste-board or similar material. The sides of the box are then covered with a suitable ornamental paper which extends 90 over the edges and partly over the top. The face-piece which has substantially the same dimensions as the top surface of the box and which is also made of pasteboard, is also covered with similar paper on one 100 side with the edges of the paper extending over the edges and for a short distance on the under side. In the finished box the face-piece is superposed on the box with

the edges coinciding and glued in such position by suitable means such as the machine herein described.

It will be noted that, in assembling the 5 box elements above described, the edges of the face-piece and the box coincide and preferably very accurately. In order to produce this result a number of difficulties may be encountered. One such difficulty 10 consists in placing the two parts together without relative sidewise movement which might tend to smear the glue on to the paper thereby spoiling the appearance of the box. Another difficulty is found in 15 properly drying the glue without warping the top of the box. In overcoming these difficulties the herein-described embodiment of the invention automatically carries the two elements of the box to a press, keeping 20 them separated the while, and places them in superposed relation, in exact alignment and in engagement with means to hold them separated. One of the elements of the box has previously had glue applied on the face 25 by which it is to be attached to the other element. By the action of the press these elements are assembled and heated to dry the glue. In order to hasten the drying of the glue, one of the press elements is perforated to permit the escape of vapor generated by the heat. Having been thus substantially dried, the likelihood of warping of the parts is very slight.

It will be noted that the stiffness and 30 thickness of the face-pieces are in some respects an advantage in handling them. These qualities are utilized in holding the box elements apart at the press where they are grasped by means engaging their side 35 edges, and in feeding the face-pieces one at a time from a suitable magazine in which they are placed.

The machine comprises a means for feeding the boxes 14 successively to a position 40 underlying a magazine containing a number of corresponding face-pieces 15 stacked vertically; a device for applying the glue to the box portions 14 in transit to such position; and a means which removes the 45 face portion 15 and a corresponding box portion 14 from their respective supply device and carries them to position at a press where the box portion and its face-piece are pressed together and dried and then 50 removed from the press by pressure of the next succeeding box thereagainst.

The supply device for conveying the 55 boxes to position adjacent the face-pieces comprises a belt conveyor 16 on which the box portions 14 are placed by hand. Belt conveyor 16 is provided with an idler pulley 17 and a power driven pulley 18 over which the belt 16 is stretched. Pulley 18 is driven by means of a chain 19, associating a sprocket 19' with a correspond-

ing sprocket 20 on a shaft 21 connected through a suitable clutch 22 to a belt driving pulley 23 associated with the main driving motor 24. The belt conveyor 16 is enclosed on two sides by a frame 25 which 70 serves as a supporting means for pulleys 17 and 18. Frame 25 also serves to keep the box portion 14 from sliding off the sides of belt conveyor 16. Belt conveyor 16 is of sufficient length to extend well outward from the rest of the working parts of the machine so that the operator may conveniently place boxes thereon.

Frame 25 is supported by suitable bracket 75 26 bolted thereto which is, in turn, supported on the main table 27 of the machine. Main table 27 is provided with suitable legs or braces 28 of any suitable character to form a rigid support therefor.

When placed on the belt conveyor 16, the 80 box portions are carried to a position underlying a cross-piece 29 where they are held against further motion in this direction. Superposed directly above this position, there is bolted to the cross-piece 29 and a similar cross-piece 30, four angular upright members 31 forming four corners of a rectangular magazine of skeleton form which is adapted to receive a number of face-pieces with that side down which is to 85 be glued to the box portion. As they lie in the supply magazine formed by the members 31, the face-pieces register exactly with the box portion lying under them on the 90 belt conveyor 16.

As a means for applying glue to the upper surface of the box portion, there is provided a vertically reciprocating pad 32 extending over the belt conveyor 16. This 95 pad is adapted to descend on the boxes as they successively pass beneath its position. They are prevented from being lifted off the conveyor by means of inwardly projecting members or strippers 33 integrally formed on the frame 25. The vertical reciprocation of pad 32 is accomplished by means of a cam 34 operating against cam follower 35 on rod 36 on which pad 32 is supported. Cam 34 is mounted on a shaft 37 which is provided with a sprocket 38 connected with another sprocket 39 by 100 means of chain 40. Sprocket 39 is mounted on shaft 41 which also carries a sprocket 41' connected by means of a chain 43 to sprocket 42 mounted on shaft 21.

At 44 there is indicated a pan filled with a suitable glue or paste to be applied to the pad 32 and, thereby, to the box portions 14. Partly covered by the glue in pan 44 is a roller 45 constantly rotating and transferring glue to another roller 46, the two rollers being directly connected by gears 47. Roller 46 transfers glue from its surface to the surface of a roller 48 which is adapted to travel back and forth from po-

sition at roller 46 to the pad 32. By means of roller 48, pad 32 is kept supplied with glue for application to the box portions 14 as they pass thereunder. The reciprocatory motion of roller 48 is accomplished by means of an arm 49 attached thereto at one end and at the other end connected with a bell crank 50 pivotally supported on table 27, and a cam 51 operating 10 against a cam follower 52 associated with the bell crank 50. Cam 51 is suitably mounted on shaft 37 and operates in synchronism with cam 34 controlling pad 32.

For feeding the box elements to the press, 15 there is provided a member 53 slidably mounted between cross-pieces 29 and 30 by means of projecting beads 54, and to which on its lower side is suitably attached an angular piece 55 extending from one end to 20 approximately the width of box portion 14 from the other end of member 53. Member 53 is adapted to slide back and forth transversely of the direction of belt conveyor 16. As it moves forward, it removes 25 a box from the conveyor and pushes it in a guide-way formed by inward projections at the extreme bottom of cross-pieces 29 and 30. At the upper surface of member 53, a portion of the surface to the depth of the 30 thickness of a face-piece 15 is cut away to a point 56 directly above the end of member 55 at which point there is formed a shoulder. In its movement carrying a box from conveyor 16, member 53 also removes 35 a face-piece from the magazine keeping them in exactly the same relative position as before, that is, in registry therewith. In this superposed relation, the box and its face-piece are removed the length of motion 40 of member 53, whereupon that member returns leaving them for the further operation of attachment. Upon such removal, the face-piece does not drop but is held between a pair of spring members 57 support- 45 ed on the sides of the cross-pieces 29 and 30. Spring members 57 are shown in detail in Fig. 10. It will be seen that, by pressure exerted against its flat length, spring member 57 will be pushed back into the slot 58 50 which is substantially equal in depth to the thickness of the spring. The natural tendency is for the spring to press outwardly and it therefore frictionally grips the sides of the face-piece pressing thereagainst to hold it from returning with member 53, and, 55 when the support afforded by that member is withdrawn these springs hold the face-piece from falling.

The reciprocating motion of member 53 60 is imparted thereto by a bell crank 59 operated by a cam 60 mounted on shaft 41, and a cam follower 61. Return motion is caused by the tension of the spring 62 on bell crank 59 and its associated cam fol- 65 lower 61.

In order to prevent more than one face-piece, at a time, from being removed from the magazine by member 53, there is provided a stop member 63 rigidly supported on members 31. Stop member 63 is adjust- 70 ed so that it allows one face piece to pass therebeneath and withholds the remaining face-pieces.

At the position in which the box portion and its corresponding face-piece are placed 75 by the member 53, there is provided a press which comprises a reciprocating plunger and a plate towards which the plunger is adapted to move for the purpose of pressing the glued surface of the box against the corresponding face-piece to thereby assemble 80 said piece and box. The plunger comprises a rod 64 on which is mounted a head 65 which fits closely the interior of box portion 14. On upward motion of the head 65, the 85 box is telescoped thereon and pressed against the face-piece 15 as shown in Fig. 7. The complementary plate 66, against which the box elements are pressed, is provided with a number of passageways or ap- 90 ertures 67 extending therethrough to the space within the press. Mounted on this plate is a block 68 provided with apertures 69 into which are placed suitable heating units, preferably electrical. Plate 66 being 95 heated by the units referred to, causes a certain amount of vapor to be formed from the heated glue on the box portion and these vapors are permitted to escape through the 100 perforations 67.

In order to adjust the press elements, cross-pieces 29 and 30 and plate 66 which is mounted thereon are provided with an adjusting screw 70 and a hand-wheel 71 by which the proper separation may be effected. 105

Motion is imparted to the plunger 64 by the cam 72 mounted on shaft 41, and which acts against cam follower 73 on plunger rod 64.

When plunger 64 is withdrawn, the box 110 portion 14 is pulled downwardly since it fits snugly on the plunger head 65. Face-piece 15, being attached to box 14, is also pulled down therewith. The completed box is stripped from the plunger head 115 65 by engagement of the inwardly projecting portions of the cross-pieces 29 and 30 with the lower edges of the box.

The completed box is pushed from the 120 guide-way by the next succeeding box portion placed by the member 53. The box falls on an apron or chute 74 leading to any suitable receptacle as a basket or other suitable conveying medium (not shown).

When the pressure exerted against the 125 box elements by the press is very heavy, the heater associated therewith may be dispensed with. It is also understood that modifications may be made adapting the structure for simultaneously feeding and op- 130

erating upon a plurality of the box elements, thus increasing the capacity of the machine.

Thus by the above construction are accomplished among others the objects previously mentioned.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:

1. In a machine of the character described, in combination, a press, and means adapted to feed box elements into spaced superposed relation in the press.

2. In a machine of the character described, in combination, a press, means adapted to feed box elements into spaced superposed relation in the press, and means whereby actuation of the press presses said elements together.

3. In a machine of the character described, in combination, a press, means adapted to feed box elements into superposed relation in the press, one of the pressing elements of the press having one or

more passageways leading to the space between the press elements, and means adapted to heat said pressing element.

4. In a machine of the character described, in combination, a press, means adapted to feed box elements into superposed relation in the press, means whereby actuation of the press presses said elements together, one of the pressing elements of the press having one or more passageways leading to the space between the press elements, and means adapted to heat said pressing element.

5. In a machine of the character described, in combination, a press, means adapted to feed box elements into spaced superposed relation in the press, means whereby actuation of the press presses said elements together, one of the pressing elements of the press having one or more passageways leading to the space between the press elements, and means adapted to heat said pressing element.

6. In a machine of the character described, in combination, a press, means adapted to feed box elements into spaced

superposed relation in the press, and means whereby actuation of the press presses said elements together comprising a reciprocal head adapted to telescope with one of said box elements.

7. In a machine of the character described, in combination, a press, means adapted to feed box elements into superposed relation in the press, said press comprising a reciprocal head adapted to telescope with one of said box elements, one of the pressing elements of the press having one or more passageways leading to the space within the press, and means adapted to heat said pressing element.

8. In a machine of the character described, in combination, a press, means adapted to feed box elements into spaced superposed relation in the press, one of the pressing elements comprising a reciprocal head adapted to telescope with one of said box elements, and a box element stripper relative to which said head moves.

9. In a machine of the character described, in combination, a press, means adapted to feed box elements into superposed relation in the press, and means adapted to frictionally grip one of said box elements for retaining it in predetermined position in the press chamber.

10. In a machine of the character described, in combination, a box supply device, a face-piece supply device, a box gluing device, a press, and means adapted to feed boxes and face-pieces from said supply devices into the press, said feeding means including devices for supporting the respective boxes and face-pieces in spaced relation while being fed.

11. In a machine of the character described, in combination, a box supply device, a face-piece supply device, a box gluing device, a press, and means adapted to feed boxes and face-pieces from said supply devices into the press, said feeding means including devices for supporting the respective boxes and face-pieces in spaced relation while being fed, the box supporting feed device including a reciprocal face-piece carrier.

12. In a machine of the character described, in combination, a box supply device, a face-piece supply device, a box gluing device, a press, and means adapted to feed boxes and face-pieces from said supply devices into the press, said feeding means including a face-piece carrier and a box pusher adapted to maintain alignment and separation of the face-pieces and boxes while being fed.

13. In a machine of the character described, in combination, a belt conveyor for boxes, a magazine for face-pieces in superposed relation to said conveyor, a face-piece carrier and a box pusher co-operative there-

- with, said carrier being movable between said conveyor and said magazine and adapted to maintain the face-pieces apart from the boxes.
- 6 14. In a machine of the character described, in combination, a belt conveyor for boxes, a box gluing device, a magazine for face-pieces in superposed relation to said conveyor, a face-piece carrier, and a box 70 pusher co-operative therewith, said carrier being movable between said conveyor and said magazine and adapted to maintain the face-pieces apart from the boxes.
- 10 15. In a machine of the character described, in combination, a belt conveyor for boxes, a magazine for face-pieces in superposed relation to said conveyor, a face-piece carrier, and a box pusher co-operative therewith, said carrier and said pusher being 75 movable between said conveyor and said magazine and adapted to remove a box and a face-piece from said conveyor and said magazine respectively and including means to maintain the box and the face-piece so 80 removed in spaced relation.
- 15 16. In a machine of the character described, in combination, a belt conveyor for boxes, a magazine for face-pieces in superposed relation to said conveyor, a face-piece 85 carrier and a box pusher co-operative therewith, said carrier and said pusher being movable between said conveyor and said magazine and adapted to remove a box and a face-piece from said conveyor and said 90 magazine respectively and including means to maintain the box and the face-piece so removed in spaced relation.
- 20 17. In a machine of the character described, in combination, a belt conveyor for boxes, a magazine for face-pieces in superposed relation to said conveyor, a face-piece carrier and a box pusher co-operative therewith, said carrier and said pusher being 95 movable between said conveyor and said magazine and adapted to remove the boxes and the face-pieces singly from said conveyor and said magazine respectively and including means to maintain the boxes and the face-pieces so removed in spaced superposed relation.
- 25 18. In a machine of the character described, in combination, a press, means adapted to feed box elements in superposed relation in the press, one of the pressing 100 elements of the press including a perforated plate.
- 30 19. In a machine of the character described, in combination, a press, means to feed box elements into superposed relation in the press, means whereby actuation of the press presses said elements together, one of the pressing elements of the press including a perforated plate, and a heater associated with said perforated plate.
- 35 20. In a machine of the character de- 105 scribed, in combination, a press, means to feed box elements into spaced superposed relation in the press, means whereby actuation of the press presses said elements together, one of the pressing elements of the press including a perforated plate, and a heater associated with said perforated plate.
- 40 21. In a machine of the character described, in combination, a press, means adapted to feed box elements into superposed relation in the press, said press comprising a plunger head adapted to telescope with one of said box elements and a perforated pressing element co-operative therewith to press the box elements together, and 110 a heater associated with said perforated element.
- 45 22. In a machine of the character described, in combination, a press, means adapted to feed box elements into spaced superposed relation in the press, and means adapted to frictionally grip one of said box elements for retaining it in predetermined spaced relation to another of said box elements within the press.
- 50 23. In a machine of the character described, in combination, a press, means adapted to feed box elements into spaced superposed relation in the press, and resilient means adapted to grip one of said box elements for retaining it in predetermined spaced relation to another of said box elements within the press.
- 55 24. In a machine of the character described, in combination, a press, means adapted to feed box elements into spaced superposed relation in the press, and springs disposed in the space adjacent the press and adapted to grip one of said box elements for retaining it in predetermined spaced relation to another of said box elements within the press.
- 60 25. In a machine of the character described, in combination, a press, a belt conveyor for boxes, a magazine for face-pieces, superposed above the belt conveyor, a reciprocal member adapted to remove a box from the belt conveyor and a face-piece from the magazine and to place them in superposed relation at the press, said reciprocal member comprising a slide having a recess therein to receive a face-piece, and a member on the lower face of the slide to push a box, the slide being adapted to hold the face-piece and box separated and in alignment.
- 65 26. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into super- 120
- 70 125
- 75 130

posed relation to each other in said press, and mechanism for actuating said press.

27. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, and mechanism for actuating said press, said means including devices for simultaneously moving a glued box and a face-piece therefor into said press.

28. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, and mechanism for actuating said press, said means including devices for guiding the boxes to and arresting them in registry with but spaced from the face-pieces in said magazine.

29. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, mechanism for actuating said press, and means adapted frictionally to grip the face-piece by its edges and thereby retain the same in the press in registry with the box therein.

30. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, mechanism for actuating said press, and means adapted to support the face-piece in said press in registry with but spaced from the box therein.

31. A machine for applying face-pieces to boxes including, in combination, a magazine adapted to support the face-pieces in a pile, a piece and box assembling press, a box gluer, means adapted to convey boxes

one by one into and out of operative relation to said gluer and thereafter convey the previously glued box, and a face-piece therefor from said magazine, into superposed relation to each other in said press, and mechanism for actuating said press, said press including a perforated pressing plate adapted to contact said face-piece and means adapted to heat said plate.

32. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, and mechanism for actuating said press, said press including a perforated pressing plate adapted to contact said face-piece and means adapted to heat said plate, and a reciprocal pressing plunger fitting the interior of said box.

33. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, mechanism for actuating said press, and means adapted to support the face-piece in said press in registry with but spaced from the box therein, said press including a perforated pressing plate adapted to contact said face-piece and means adapted to heat said plate.

34. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, mechanism for actuating said press, and means adapted to support the face-piece in said press in registry with but spaced from the box therein, said press including a perforated pressing plate adapted to contact with said face-piece and means adapted to heat said plate, and a reciprocal pressing plunger fitting the interior of said box.

35. A machine for applying face-pieces to boxes including, in combination, a magazine adapted to support the face-pieces in a pile, a piece and box assembling press, a box gluer, means adapted to convey boxes

one by one into and out of operative relation to said gluer and thereafter convey the previously glued box, and a face-piece therefor from said magazine, into superposed relation to each other in said press, mechanism for actuating said press, and means adapted frictionally to grip the face-piece by its edges and support the same in said press in registry with but spaced from the box therein, said press including a perforated pressing plate adapted to contact said face-piece and means adapted to heat said plate.

36. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, mechanism for actuating said press, and means adapted frictionally to grip the face-piece by its edges and support the same in said press in registry with but spaced from the box therein, said press including a perforated pressing plate adapted to contact said face-piece and means adapted to heat said plate, and a reciprocal pressing plunger fitting the interior of said box.

37. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, and mechanism for actuating said press, said means including devices for guiding the boxes to and arresting them in registry with but spaced from the face-pieces in said magazine, and means adapted to support the face-piece in said press in registry with but spaced from the box therein.

38. A machine for applying face-pieces to boxes including, in combination, a magazine adapted to support the face-pieces in a pile, a piece and box assembling press, a box gluer, means adapted to convey boxes one by one into and out of operative relation

to said gluer and thereafter convey the previously glued box, and a face-piece therefor from said magazine, into superposed relation to each other in said press, and mechanism for actuating said press, said means including devices for guiding the boxes to and arresting them in registry with but spaced from the face-pieces in said magazine, and means adapted to support the face-piece in said press in registry with but spaced from the box therein, said press including a perforated pressing plate adapted to contact said face-piece and means adapted to heat said plate.

39. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, mechanism for actuating said press, said means including devices for simultaneously moving a glued box and a face-piece therefor into said press, and means adapted to support the face-piece in said press in registry with but spaced from the box therein.

40. A machine for applying face-pieces to boxes including, in combination, a magazine adapted to support the face-pieces in a pile, a piece and box assembling press, a box gluer, means adapted to convey boxes one by one into and out of operative relation to said gluer and thereafter convey the previously glued box, and a face-piece therefor from said magazine, into superposed relation to each other in said press, and mechanism for actuating said press, said means including devices for simultaneously moving a glued box and a face-piece therefor into said press, and means adapted frictionally to grip the face-piece by its edges and support the same in said press in registry with but spaced from the box therein.

In testimony whereof I affix my signature, in the presence of two witnesses.

HARRY K. DICKERMANN.
